UNITED STATES PATENT OFFICE.

WILLIAM H. BURT, OF WATERBURY, CONNECTICUT, ASSIGNOR TO WATERBURY MFG. CO., OF WATERBURY, CONNECTICUT, A CORPORATION.

SWITCH-PLATE.

1,144,107.

Specification of Letters Patent. Patented June 22, 1915.

Application filed November 22, 1914. Serial No. 873,614.

To all whom it may concern:

Be it known that I, WILLIAM H. BURT, a citizen of the United States, residing at Waterbury, in the county of New Haven and State of Connecticut, have invented a new and useful Improvement in Switch-Plates; and I do hereby declare the following, when taken in connection with the accompanying drawings and the characters of reference marked thereon, to be a full, clear, and exact description of the same, and which said drawings constitute part of this application, and represent, in—

Figure 1 a face view of a switch plate constructed in accordance with my invention. Fig. 2 a rear view of the same. Fig. 3 a sectional view on the line *a*—*b* of Fig. 1. Fig. 4 a sectional view on the line *c*—*d* of Fig. 1, Figs. 3 and 4 being on an enlarged scale.

This invention relates to an improvement in switch plates or covers for switch boxes. In the usual construction these switch plates comprise a plate with an opening which is closed by a hinged cover or covers; and when two covers are employed, one is hinged above the other, the two closing the opening in the plate, and these covers are notched at their adjoining edges to form a circular opening for the passage of conducting wires.

The object of this invention is to provide simple and convenient means for hinging the covers to the plate in such a way that the means for hinging will not be apparent from the outside, and the invention consists in the construction hereinafter described and particularly recited in the claims.

As herein shown, I employ a switch plate 2 of the desired dimensions formed with an opening 3 generally rectangular. This opening is partially closed by two doors 4 and 5. If two doors are employed their meeting ends are formed with semi-circular notches to provide a central opening 6 through which conducting wires may extend. These doors are hinged to the plate by mounting in the rear of the plate transverse bars 7 and 8 which extend across the opposite ends of the opening 3 if two doors are employed, or across one end if only one door is used. These bars have their ends 8^a turned outward and passed through perforations 9 in the plate 2 on opposite sides 65 of the opening 3, and the outer ends of these

perforations are countersunk to provide a chamber 10 in which the extreme end 11 of the bars may be upset whereby the bars are firmly riveted to the plate and in such a way that when the plate is finished the ends 60 of the bar being of the same material as the plate are practically invisible. In the drawing it is necessary to employ a line to indicate these ends, but when the plate is finished the ends cannot be detected except by 65 the most careful inspection and frequently only with the aid of a strong magnifying glass. Secured to the rear of the doors 4 and 5 are hinge plates 12, the upper ends 13 of which are slightly bowed to engage with the 70 bars, and these hinge plates are secured to the doors by rivets 14 which extend through perforations 15 in the door, the perforations being countersunk at their outer ends to form a chamber 16 in which the ends 17 of 75 the rivets are upset; and like the ends of the bars 7 and 8, the ends of these rivets cannot be detected when the plates are finished. By thus upsetting the rivets in countersunk recesses, a very firm connection is 80 made between the parts, and as before stated, the ends of the bar and rivets are ground off flush with the face of the plate and cannot be detected so that they do not mar the finished appearance of the completed switch plate. 85

I claim:—

1. A switch plate formed with a central opening, a door adapted to fit said opening, said door formed with perforations countersunk in the outer face, a bar extending across said opening, means for holding the ends of the bar, a hinge plate secured to the rear face of the door by rivets extending through the perforations in the door the ends of the rivets upset within the countersunk portions of the perforations in the door, said hinge plate engaging with said bar whereby the doors are hinged to the plate. 96

2. A switch plate formed with a central opening and with perforations on opposite sides thereof, the outer ends of said perforations countersunk, a door adapted to fit said opening, said door formed with perforations countersunk in the outer face of the door, a bar extending across said opening and having its ends turned outward and passed through said perforations in the plate, and the outer ends of the bar upset 105 110

in the countersunk portions of the perforations, a hinge plate secured to the rear face of said door by rivets extending through the perforations in the door the ends of the 5 rivets upset within the countersunk portions of the perforations in the door, said hinge plate engaging with said bar whereby the doors are hinged to the plate.

3. A switch plate having a rectangular 10 opening and formed with countersunk perforations on opposite sides of said opening near the ends thereof, bars extending across said opening at the rear of said plate, the ends of said bars extended outward through 15 said perforations and upset in the countersunk portions thereof, two doors located in

said opening in the plate, said doors each formed with two perforations countersunk in their outer faces, hinge plates secured to the doors by rivets passing through said perforations in the doors, said rivets upset in the countersunk portions of said openings and the ends of the rivets and ends of the bars ground flush with the face of the plate.

In testimony whereof, I have signed this 25 specification in the presence of two subscribing witnesses.

WILLIAM H. BURT.
